ROCK DRILL

Paul H. Nast, West Springfield, Mass., assignor to
Chicago Pneumatic Tool Company, New York,
N. Y., a corporation of New Jersey

Application September 24, 1945, Serial No. 618,277

1 Claim. (Cl. 255—45)

1

This invention relates to rock drill mechanisms of the drifter type and more particularly to a buffer arrangement therefor.

It is an object of the present invention to provide a rock drill mechanism with a buffer arrangement to prevent sudden shock in stopping the drill motor at the end of its rearward travel.

Another object is to prevent the rock drill feed nut from being locked against reversal of rotation on the next forward movement of the drill motor.

For other objects and for a better understanding of the invention, reference may be had to the following detailed description taken in connection with accompanying drawings, in which:

Fig. 1 is a top plan view, partly in section, of a rock drill mechanism embodying the features of the invention;

Fig. 2 is a side elevational view of the rock drill and mounting assembly with sections thereof left out;

Fig. 3 is a longitudinal section through the rear section of the drill mechanism including the feed motor, reduction gearing, and cylinder back plate;

Fig. 4 is a rear end view, in elevation, showing the feed and drill motor control valve handles and the air and cooling water inlet pipes; and

Figs. 5, 6 and 7 are respectively fragmentary cross-sectional views taken respectively along lines 5—5, 6—6, and 7—7 of Fig. 1 and looking forwardly.

Referring particularly to Figs. 1, 2 and 3, the rock drill mechanism or assembly generally comprises a guide shell 11, having a cone 12 for attaching the shell to any suitable support and a stationary feed screw 13, and a drill motor 14 carrying a drill steel 16. On the rear end of the drill motor housing, there is stacked in order, a cylinder back plate 17, a reduction gear housing 18 and a feed motor housing 19. These parts are secured to the drill motor housing by through-bolts 21 located respectively at opposite sides of the parts. On the rear of the feed motor housing 19 are drill and feed motor valve handles 22, 23 adapted to respectively operate drill and feed motor control valves 24, 26 located in the feed motor housing 19 at opposite sides of the feed motor rotor 27, Figs. 4, 5.

Air enters the drill through a single air inlet nipple 28 on the reduction gear housing 18, and is directed through ports 29, 31 therein to the drill and feed motor control valves 24, 26. As viewed in Fig. 5, these valves are in their off positions so that the drill is not in operation.

2

The feed motor control valve 26 is held in any one of several positions by a detent plunger 32 and a spring 33, retained in the feed motor housing by a spring plug 34. The plunger 32 is limited in its axial movement by a pin 35 and a cooperating slot 36 in the plunger 32. This feed motor control valve 26 has three large indentations 37, 38 and 39 which respectively retain the valve in the off, reverse and forward positions. Between the indentations 37 and 39 is a series of small indentations 41 which, when aligned with the plunger 32, hold the valve 26 in partly opened forward positions so that the feed motor may be throttled on forward speed from zero to maximum.

The feed motor rotor 27 has six milled slots 42 carrying radially-slidable blades 43, and is supported in two roller bearings 44, 45 mounted respectively in feed motor front and rear end plates 46, 47. A rotor liner 48 is disposed between the end plates 46, 47 and its inner diameter is eccentrically bored to give the rotor blades 43 an outward and inward sliding movement. This assemblage, including rotor 27, front 20 and rear end plates 46, 47, and rotor liner 48 is retained in the feed motor housing against angular displacement by a dowel 51, which projects at one end into the gear housing 18. A spring washer 52 holds the end plates 46, 47 and the liner 48 tightly together to prevent any leakage of air therebetween.

On the forward end of the rotor 27, and extending into the reduction gear housing 18, is a pinion 53 adapted to mesh with an idler gear 54 having a replaceable bushing 55 rotatable on a pin 56. Idler gear 54 has other gear teeth 57 which mesh with gear teeth 58 of a feed screw nut 59 on feed screw 13. This feed screw nut is journaled between a bearing 61 on the gear housing 18 and a bearing 62 on the cylinder back plate 17. The gear pin 56 is also supported on both the gear housing 18 and back plate 17.

Guide shell 11 has a front feed screw support 64, Fig. 1, for supporting the forward end of the feed screw 13, and a buffer spring case cover 65 for supporting the rear end thereof. The drill motor 14 is slidable in guide-ways 66, Figs. 5, 6, 7. A rear handle 67 is connected to shell rods 68 and 69 by nuts 71. These rods extend the full length of the shell from the buffer spring case cover 65 and rear handle 67 to the front feed screw support 64. The rear end of the feed screw has six splines 73 that 55 act as keys upon matching key-ways 74 in the

buffer spring case cover 65 to retain the feed screw against rotation.

If the drill is not stopped before it arrives at the rearward end of its travel, the rear end of the feed screw nut 59 contacts a buffer washer 75, which, in turn compresses a buffer spring 76 to ease the drill into its final stopping position, both surrounding the feed screw and within a buffer spring case 77. The rearward travel is generally at full speed of the feed motor. The impact of the drill is cushioned thereby permitting the motor to stall before the axial thrust against the feed nut becomes excessive. The buffer arrangement thus prevents sudden shock in stopping the feed motor and the feed nut from being locked with a stop in such a manner as would prevent reversal of rotation of the feed motor.

The reduction gear housing 18 has an oil reservoir 78 in which the rotor pinion 53 and idler gears 54, 57 are enclosed. This reservoir is filled through a threaded hole closed by an oil plug 79, Fig. 4.

In assembling the drill and feed motors, the cylinder back plate 17 is first fitted upon the rear end of the drill motor housing 14, Fig. 3. A dowel pin 81 is passed through the cylinder back plate 17 and extended into the drill motor housing 14 whereby to prevent relative angular movement therebetween. The dowel pin 81 also projects rearwardly from the cylinder back plate and is received by an opening 82 in the gear housing 18 as the latter is in turn stacked upon the back plate. The same dowel pin 81 thus prevents angular movement of the gear housing 18.

In turn, the feed motor housing 19, including its rotor parts, is stacked upon the gear housing 18. Relative angular movement between the feed motor 19 and the gear housing 18 is prevented by the dowel pin 51. It will now be apparent that by means of two dowel pins 51, 81 the stacked parts are retained against relative rotation and held in angular alignment with the cylinder 14. These same parts are retained against axial displacement by the through-bolts 21 extending through lugs 83, 84 on the respective drill and feed motor housings 14, 19.

The drill motor throttle valve 24 is operated by the handle 22 and is held in its adjusted positions by a detent plunger 86 urged upwardly by a spring 87 and retained in the feed motor housing by a spring plug 88. This valve 24 has four indentations 90, 91, 92, 93, Fig. 7, that cooperate with the plunger 86 to respectively retain the valve in off, light run, run, and blow positions.

Water for the drill motor to settle dust resulting from the drilling operation enters the rear end of the feed motor housing 19 through a nipple 94 from a hose 95, Fig. 4. The water upon entering the feed motor housing is received in a chamber 96, Fig. 3, from where it passes by way of a passage 97 to a threaded recess 98 adapted to be closed by a screw plug 99. A fluid delivery tube 101 is inserted through the assembled parts by way of the threaded recess 98 and 65 is held in place by the screw plug 99. The tube 101 enters the drill motor and delivers water to the drill steel in the manner shown in the patent to Lear 2,177,391. A packing gland 102 in the cylinder back plate 17 prevents leakage of oil from the oil reservoir 78 along the tube 101 and toward the drill motor 14. The plug 99 forces a flange 103 on the tube against a washer 104 that compresses sealing rubber 105 to prevent leakage of the water in the threaded recess 98 75

to the feed motor. Any air pressure that may be built up within the feed motor housing 19 is vented through the air vent passage 106 to the atmosphere.

As the feed throttle valve handle 23 is turned upwardly, air is admitted to the feed motor blades. Air entering nipple 28 in the gear housing 18 passes through passage 31, Fig. 1, central opening 107, radially-extending valve port 108, 10 graduated groove 109, and finally as the valve is turned further, housing port 110, liner groove 111, circumferentially-spaced liner ports 112, to the spaces between rotor blades, Fig. 7. Rotor 27 is rotated clockwise driving idler gears 54-57 counter-clockwise and in turn feed screw nut 59 is driven clockwise on the stationary feed screw 13 to advance drill motor toward the work. The graduated groove 109 permits limited amounts of air to be supplied to the blades and its position can be altered to control the speed of the feed motor so that the feed motor may be adjusted to advance the drill motor at the same rate as the drilling speed.

At the same time that air is admitted to the blades to turn the rotor, air is passed to two housing holes 114, Fig. 7, at the ends of the rotor liner 48. In registry with these holes 114 are front and rear end plate holes 115, Fig. 5, directing air to segmental grooves 116 in the respective front and rear end plates 46, 47. As any of the six blade slots 42 register with the segmental plate groove 116, air is directed under the blades 43 to hold them out against the eccentric liner bore. For a more complete description and illustration of a conventional arrangement for directing live air from a segmental groove in the end plate to the inner edge of the blade, reference is made to Amtsberg Patent 2,037,358, April 14, 1936, and particularly to Fig. 11, thereof.

As the blades 43 pass liner exhaust holes 117 registering with housing exhaust holes 118 which lead into a main exhaust hole 119, the air between the blades is exhausted to atmosphere. In addition to the liner exhaust holes 117, there are two exhaust holes 121, Fig. 5, one in the front end plate and one in the rear end plate, that also register with the housing holes 118 thereby to increase the main exhaust capacity. Such air as is ahead of the blades after they have passed the exhaust holes 117, 121, is exhausted through auxiliary exhaust port 122, Fig. 7. The exhaust air leaves the blades through liner ports 123, liner groove 124, housing port hole 125, circular exhaust groove 126 in the valve 26, Fig. 6, straight exhaust groove 127 in the valve 26, and circular exhaust groove 128 in the valve 26.

Any live air in the slots 42 under the blades 43 is exhausted into segmental grooves 131 and holes 132 in the front and rear end plates 46, 47, through the valve in the above manner and out auxiliary exhaust port 122.

When the feed motor throttle valve 26 is turned and plunger 32 is located in indentation 38 thereof, air is admitted to the feed motor housing through valve port 133, housing port 125, liner groove 124, liner holes 123, and rotor 27 is caused to rotate in a counter-clockwise direction. The idler gear 54 is driven clockwise, the feed screw counter-clockwise and the drill is moved rearwardly and away from the work. The main air will be exhausted from the rotor in the same manner as above described, through the liner ports 117, housing ports 118 and main discharge

passage 119 to the atmosphere. The use of grooves 116 and 131 in the end plates will be reversed. Air entering rotor slots 42 underneath blades 43 thus passes from groove 131 and is exhausted to groove 116.

Operation of the drill motor 14 is the same as with the conventional drifter. The difference here is that the back head of the drill motor is eliminated and the special back plate 17 is used. The usual air nipple, throttle valve, and water connections that are on the back head of the conventional drill motor are now in the present invention in the gear housing and feed motor housing.

A live air chamber 136 is provided in the cylinder back plate 17 to supply air to the distributing valve (not shown) in the drill motor. The drill motor may be constructed generally along the lines of the drill motor shown and described in the above-mentioned patent to Lear 2,177,391. Emergency blow holes 137, Fig. 3, 138, 139, Figs. 5, 6, for the drill motor, are also provided in the cylinder back plate 17. When the drill motor throttle valve 24 is turned to the left and toward the running position, a valve port hole 141 registers with a passage 142 in the parts, Fig. 5, that connects with the drill motor supply chamber 136 in the cylinder back plate 17. Live air in a valve central hole 143 coming from the air in the nipple 28 by way of the passage 29 in the gear housing 18, is thus directed to the drill motor supply chamber 136 causing the drill motor automatic valve to operate.

When the plunger 86 is in the valve indentation 91, Fig. 7, so that holes 141 and 142 are only partially registered with each other only a limited amount of air is allowed to pass thereby, the drill motor will be run at a retarded speed. When plunger 86 is in indentation 92 the valve 24 is held so that holes 141 and 142 are fully registered and the drill motor runs at full speed.

When the plunger 86 is in the indentation 93, the throttle valve is in the emergency blow position. Valve port hole 146 registers with a housing passage 147 and supplies air to cylinder back plate port 137 by way of a passage 148 extending through the parts, Figs. 3, 5. Also, air will pass to blow holes 138, 139. Live air leaves central valve passage 143 and passes through valve port hole 151, Fig. 6, valve groove 152, which will be in register with passage 153, and enters the holes 138, 139.

It should now be apparent that a built-in feed

motor of simple construction has been provided wherein the various parts, which are stacked upon the rear end of the drill motor, are simply retained thereon against angular and axial displacement. That the air supply is made by a single connection and the drill and feed motor valves are located in the feed motor and their operating handles are both on the rear end of the feed motor. That adequate means is provided on the guide shell to cushion the rearward movement of the drill motor to prevent sudden shock in stopping the feed motor at high speed.

While various changes may be made in the detail construction of this rock drill mechanism, it shall be understood that such changes shall be within the spirit and scope of the present invention as defined by the appended claim.

What is claimed is:

In a rock drill mechanism, a guide shell, a stationary feed screw having an unthreaded portion, a feed screw nut rotatable on the feed screw, buffer means at the rear of the guide shell comprising a casing having a central longitudinal aperture, a cover for the casing disposed in the rear thereof, an annular flange on the casing projecting into the central aperture, a sleeve member mounted on the unthreaded portion of the feed screw and disposed within the aperture of the casing, an annular external flange on the sleeve to cooperate with the casing flange to prevent axial movement of the sleeve in one direction, compression spring means arranged between the casing, the cover, and the sleeve whereby to prevent sudden shock of the moving parts upon the rearward terminal movement of the feed screw nut.
